DUPLICATING APPARATUS

Henry Auguste Gripekoven, Bronxville, N.Y., assignor to Visirecord, Inc., New York, N.Y., a corporation of
New York

Application May 27, 1958, Serial No. 51,095

Term of patent 14 years

(Cl. D64—11)

Fig. 1 is a side elevational view of a duplicating apparatus showing my new design, the side opposite thereto being substantially similar in appearance;

Fig. 2 is a front elevational view;

Fig. 3 is a bottom plan view, and

Fig. 4 is a rear elevational view thereof on reduced scale.

I claim:

The ornamental design for a duplicating apparatus, as shown and described.
